HIGHWAY GATE

Filed Dec. 5, 1931

FIG. 1

UNITED STATES PATENT OFFICE

MORRIS MACDONALD DILLEY AND JAMES H. FRASER, OF COLUMBUS, INDIANA, ASSIGNORS TO AUTOMATIC SAFETY SIGNAL GATE CO., OF COLUMBUS, INDIANA, A CORPORATION

HIGHWAY GATE

Application filed December 5, 1931. Serial No. 579,150.

This invention relates to a gate structure which is adaptable for protecting a highway crossing of a railroad or the like.

The chief object of this invention is to improve and simplify gate structures of the character indicated and in such a manner that the gate arm may be tilted through a power mechanism and while supported by a rotatable head and each movement being relatively independent of the other and without interference from the other.

The chief feature of the invention consists in the particular arrangement of and the simplification of the parts necessary to accomplish the foregoing object.

One particular feature of the invention consists in the mounting of the head upon a supporting pedestal in such a manner that the head is normally constrained toward seated position upon the pedestal and the same constraining force is arranged to automatically return the head when turned and upon release from the turning force.

Another particular feature of the invention consists in mounting the power for tilting the gate arm within and near the base of the pedestal the said mounting including a universal joint arrangement whereby the turning of the head does not interfere with the tilting of the gate arm.

Another feature of the invention consists in the coaxial mounting of the head upon the pedestal and the gate tilting power mechanism within the pedestal and in substantially axial alignment.

The full nature of the invention will be understood from the accompanying drawing and the following description and claims:

Fig. 1 is a sectional view of the pedestal, the pedestal supported portion of the gate and mechanism enclosed by the pedestal.

Fig. 2 is a top plan view of the pedestal with the pedestal supported portion and mechanism removed.

Fig. 3 is a sectional view taken on line 3—3 of Fig. 1 and in the direction of the arrows.

In the drawing 10 indicates a hollow frusto-conical pedestal suitably supported upon a base 11. Access to the pedestal may be ob-

tained through the door 12, the latter being retained in closed position by the latch 13 which may or may not be locked, provision for the former being provided at 14. The upper end of the pedestal includes a spider construction 16 which has two of its arms 17 spaced at a central angle greater than 180°. The hub 18 of the spider is suitably recessed as at 19. Mounted therein is a ball race or anti-friction construction 20. A similarly arranged spider construction 21 is rigid with a head 22 and the head 22 has a depending skirt 23 that overlaps the top of the pedestal and prevents drainage from the head passing into the pedestal. The pedestal also includes the cover 24 similarly skirted at 25 for a similar purpose.

The pedestal rotatably mounts the head structure. Upon the axis of rotation thereof and transverse thereto, is a rock shaft 26 which has secured to it a gate arm 27, the same being of multiple character as indicated at 28, the extension 29 being arranged to tilt when necessary with respect to the portion 27 so that if the gate arm descends upon a vehicle on the crossing, the portion 29 will remain stationary relative to the vehicle while the portion 27 even though the latter is being tilted. After the vehicle has passed from beneath the portion 29, the connection 28 is of such character that portion 29 is automatically realigned with portion 27 in the crossing protecting position.

Within the head structure there is suitably mounted and secured to the rock shaft 26, a lever arm 30 which has a cylindrical portion 31. The outer end of portion 31 is provided with an annular groove 32. A yoke 33 is of angular type. The arms thereof straddle the cylindrical portion 31 and a retaining bolt 34 connects the two arms and seats in the annular groove 32. With this construction, the member 33 may pivot on the spindle portion 31 to the desired degree. The offset end of yoke 33 includes a pivot receiving opening 35 and mounted therein is a pivotal connecting bolt 36 that seats in the eye portions 37 of the ears of a threaded connecting member 38. A rod 39 has a threaded connection with the threaded portion 38 and

said rod constitutes the piston rod of the power structure. The connections between said rod 39 and said lever arm 30 include two pivots at right angles which constitute a universal joint.

Substantially coaxially positioned beneath the turning mechanism of the head, is a universal joint construction 40 which includes a ball 41 connected by a neck 42 to a cylinder head 43. The cylinder 44 is supported thereby and within the cylinder is mounted the piston 46 carried by one end of the rod 39. It will be apparent that the cylinder and piston rod construction is tilted with reference to the axis of the head.

The spider constructions before mentioned, it will be recalled, include a spacing greater than 180° and in fact, said spacing is approximately 200° more. In said spacing is positioned said piston rod 39 so that in the relative movement between the head and the pedestal, the piston rod 39 turns with the head and does not engage or receive any interference from the spider arms.

It will also be observed that in view of the coaxial positioning, turning movement of the head does not cause any relatively longitudinal movement of the piston or piston rod with respect to the cylinder; so that the gate tilting and the head turning movement are noninterfering with respect to each other.

One form of supplying an operating medium to the cylinder is illustrated and herein the same includes a supply line 50 which communicates with the apertured portion 51 of the base 40. The ball and neck 41 and 42 respectively are shown apertured as at 52 and 53 respectively, so that no matter what position the cylinder has been tilted, it will always be in communication with the supply line 50. Suitable control means are provided for controlling the supply and discharge of fluid under pressure to and from said cylinder respectively but are not illustrated herein.

In the present invention, the gate arm is shown provided with a counterweight arrangement 54 and said weight is herein illustrated as arranged to tilt the gate arm into the vertical position. In other words, the present disclosure is such so that pressure supplied to the lower end of the cylinder 44 positively lowers the gate. By a different leverage arrangement and different counterweighting, the counterweight may be arranged to lower the gate and the fluid pressure positively raise the gate in opposition to the counterweight. In that event, release of pressure from the cylinder will permit said counterweight when thus connected to the gate arm to lower the gate into crossing guarding position.

Likewise without departing from the invention in its patentable features, the cylinder and piston construction may be arranged

for supplying fluid under pressure to opposite sides of the piston and alternately and in that event, the counterweighting may be eliminated and the gate will be raised and lowered positively by the power means of fluid pressure character. All of the aforesaid forms of power operation are considered to be the full equivalent so far as the present disclosure is concerned.

Mechanism for automatically returning the head when it has been turned from out of guarding position into an intermediate position between that and parallel to the road, includes a co-operative connection between the head and the pedestal. Rigid with the spider 21 and suitably secured thereto, is a depending shaft 60. Shaft 60 is rotatably mounted in the hub 18 of the spider 16 of the pedestal and the hub 21 bears on the anti-friction race 20 so that the friction in the turning movement is materially reduced. This shaft 60 immediately below its rotative mounting in the hub 18 of the pedestal spider, includes a pair of opposite flat faces 61.

The hub 62 includes an aperture therein with a pair of opposite flat faces 63 and arcuately connecting portions 64. The diameter of the arcuate connecting portions and the spacing is slightly greater than the diameter of the shaft 60 while the width of the face 63 and the spacing between the faces is slightly greater than the same of the portions 61 of the shaft 60; so that the hub 62 has a so-called "sloppy" fit and is slidably mounted on the shaft 60 and is non-rotatably mounted thereon also.

Secured to the pedestal inner wall and near the upper end, is a cam track construction 65. Herein a pair of spaced cam tracks is disclosed. The hub 62 includes a pair of arms 66 that extend radially therefrom and each terminates in a pivotal support 67 that mounts a roller 68 which may, if desired, be pivotally supported on the end of the arm at 67 and through an anti-friction construction. Roller 68 constitutes the cam followers.

It rides on the cam track 65. The lower end of the hub 62 bears on a washer 69. A coil spring 70 has one end bearing on the opposite face of said washer and is concentric with said shaft. The lower end of the shaft has an adjustable bearing construction 71 against which the lower end of the spring bears.

As the head is turned, the arms 66 are necessarily turned with the shaft 60 rigid with the head. Said arms as they turn, since supporting the rollers 68 which are in engagement with the cam track 65 and the spring 70 bears on the hub, necessarily move downwardly as the turning increases. In other words, the coil spring which normally tends to extend itself, is compressed in the movement of the cam followers. Thus, the spring 130

is provided with additional force so that when the head is released from the initial turning force, said spring forces the hub 62 upwardly and in this upward movement, there is imparted to the shaft a turning movement, because the cams 68 follow the track 65. The spring 70, therefore, has a double duty. It normally holds down the head upon the pedestal, because the upper end of the spring bears on the hub 62, the upward movement of which is limited by the contact of the roller followers 68 upon the cam 65. The other duty of the spring is to insure positive and automatic return of the head to the initial position when forcibly turned from the predetermined position.

It will also be observed that the shaft 60 does not extend to the bottom of the pedestal but terminates a considerable distance above the same so that the universal joint, before mentioned, may be, if and when desired, substantially aligned with the axis of said shaft 60 and preferably the end of the shaft 60 is positioned such that the coil spring and the adjustable retainers thereon do not interfere with either the piston rod or the cylinder in the swinging movement thereof occasioned by the turning of the head for the rod and the piston move therewith.

It also will be noted that the power mechanism is universally mounted at its lower end and is substantially universally connected at its opposite end to the gate arm actuating lever.

The invention claimed is:—

1. In combination a hollow pedestal, a head horizontally rotatable thereon, a gate arm pivotally mounted upon the head for vertical movement, a vertical shaft carried by said head and operatively connected to the pedestal, arcuate cam means carried by the pedestal, cam follower means supported by said shaft within the pedestal and normally constrained toward cam engagement, said arcuate cam means being downwardly directed, and spring means coaxial with the shaft and operatively bearing at one end upon the cam follower means, the said shaft and follower means being non-rotatably associated together and having relative longitudinal movement whereby rotation of the head causes cam follower means movement along the shaft for loading the spring for automatic return of the head and cam follower means to initial position upon release from the constraining head turning force.

2. In combination a hollow pedestal, a horizontally rotatable head mounted thereon, a gate arm pivotally supported upon the head for vertical movement, a cylinder piston construction positioned within the pedestal, a universal joint construction arranged to support one end of said construction at the base of the pedestal, the other end of said construction being operatively connected to the

gate arm for tilting the arm in one direction.

3. In combination a hollow pedestal, a horizontally rotatable head mounted thereon, a gate arm pivotally supported upon the head for vertical movement, a cylinder and piston construction positioned within the pedestal, a universal joint connection between the arm and construction, and a universal joint mounting for the construction.

4. In combination a hollow pedestal, a horizontally rotatable head mounted thereon, a gate arm pivotally supported upon the head for vertical movement, means adjacent the head and within the pedestal operatively arranged to retain the head thereon and constrain the head to return the same to initial position when turned, a cylinder and piston construction within the pedestal and having one end operatively connected to gate arm for tilting same in one direction, a universal joint construction arranged to support the other end of the piston and cylinder construction directly beneath said means whereby turning of the head does not interfere with gate arm tilting, said means terminating in spaced relation relative to the cylinder and piston construction.

5. In combination a pedestal including a transverse head support, a head rotatably supported thereby, a gate arm pivotally supported by the head for vertical movement thereon, a shaft structure rotatably associating the head and the head support and terminating beneath the latter and at appreciable distance above the bottom of the pedestal, yielding means associated with the shaft for normally retaining the head on the pedestal, downwardly directed cam means carried by the pedestal near the upper end thereof, cam followers engaging said cam means, cam follower support means non-rotatably and slidably mounted upon said shaft and operatively associated with said yielding means, whereby the cam followers normally engage the cam means and when the head is turned will automatically cause the return of the head to the initial position upon release from the head turning force, power means mounted in substantial alignment with the shaft and universally mounted for conical swinging movement to correspond with head turning movement, the shaft and yielding means being entirely within the cone of movement of the power means for non-interference therewith, and means connecting the power means and the gate for tilting of the latter in one direction.

6. In combination a pedestal including a transverse head support, a head rotatably supported thereby, a gate arm pivotally supported by the head for vertical movement thereon, a shaft structure rotatably associating the head and the head support and terminating beneath the latter and at appreciable distance above the bottom of the ped-

estal, yielding means associated with the shaft for normally retaining the head on the pedestal, downwardly directed cam means carried by the pedestal near the upper end thereof, cam followers engaging said cam means, cam follower support means non-rotatably and slidably mounted upon said shaft and operatively associated with said yielding means, whereby the cam followers normally engage the cam means and when the head is turned, cause automatic return of the head to the initial position upon release from the head turning force, power means mounted in substantial alignment with the shaft and universally mounted for conical swinging movement to correspond with head turning movement, the shaft and yielding means being entirely within the cone of movement of the power means for non-interference therewith, and a universal joint connection between the power means and the gate for tilting of the latter in one direction.

In witness whereof, we have hereunto affixed our signatures.
